ARM AND WRIST SUPPORT

Hans R. Lehneis, Merrick, N.Y., assignor to
New York University

Filed July 8, 1971, Ser. No. 160,993

Term of patent 14 years

Int. Cl. D24—04

U.S. Cl. D83—1 E

FIG. 1 is a perspective view looking from the top and left side of an arm and wrist support embodying my new design; and

FIG. 2 is a perspective view of the arm and wrist support of FIG. 1 rotated 180° about its transverse axis.

I claim:

The ornamental design for an arm and wrist support, substantially as shown.
